UNITED STATES PATENT OFFICE

LAWRENCE L. FRANK, OF LOS ANGELES, CALIFORNIA, ASSIGNOR TO VAN DE KAMP'S HOLLAND DUTCH BAKERS, OF LOS ANGELES, CALIFORNIA, A CORPORATION OF CALIFORNIA

DESIGN FOR A CAKE

Application filed December 5, 1927. Serial No. 24,392. Term of patent 3½ years.

To all whom it may concern:

Be it known that I, LAWRENCE L. FRANK, a citizen of the United States, residing at Los Angeles, in the county of Los Angeles and State of California, have invented a new, original, and ornamental Design for Cake, of which the following is a specification, reference being had to the accompanying drawings, forming a part hereof.

In the drawings:—

Figures 1 and 2 are perspective views showing the cake of my design, Figure 2 being a continuation of the design shown in Figure 1.

I claim:

The ornamental design for a cake as shown and described.

Signed at Los Angeles, California, this 28th day of November, 1927.

LAWRENCE L. FRANK.
